ANTIBIOTIC DISC CARTRIDGE STORAGE AND DISPENSER

Daniel M. Pina, 127 W. 96th St., New York, N.Y.
10025, and T. Justin Pressman, 18A Garden Ter-
race, North Arlington, N.J. 07032

Filed July 12, 1968, Ser. No. 12,715

Term of patent 7 years

Int. Cl. D9—04; D3—99

U.S. Cl. D52—2

Fig. 1.

Fig. 2.

Fig. 3.

FIGURE 1 is an exploded perspective view of our new design of an antibiotic disc cartridge storage and dispenser.

FIG. 2 is an assembled perspective view thereof.

FIG. 3 is an end elevational view thereof.

The ampoules illustrated in broken lines are shown for illustrative purposes only.

We claim:

The ornamental design for an antibiotic disc cartridge storage and dispenser, substantially as shown and described.
